ADJUSTABLE FLOWER POT HOLDER

Samuel P. Kelly, 806 Grand Ave.,
Fort Worth, Tex. 76106

Filed Oct. 27, 1970, Ser. No. 25,686

Term of patent 14 years

Int. Cl. D11—02

U.S. Cl. D35—3

FIG. 1

FIG. 2

FIG. 3

FIG. 1 is a front elevational view of an adjustable flower pot holder showing my new design.

FIG. 2 is a side elevational view.

FIG. 3 is a bottom plan view.

The broken lines representing the flower pot are shown for illustrative purposes only.

I claim:

The ornamental design for an adjustable flower pot holder, as shown and described.
